MACHINE FOR APPLYING FOLDERS TO
CANSHerbert W. Kagley, Lindsay, Calif., assignor to
Lindsay Ripe Olive Company, Lindsay, Calif.,
a corporation

Application December 6, 1938, Serial No. 244,233

10 Claims. (Cl. 216—55)

This invention relates to the canning art and has particular utility in the application of folders to cans, a practice which is coming into fairly wide use in the canning art. These folders generally contain instructions or suggestions as to how the contents of the can may be most profitably used.

It is an object of my invention to provide an improved machine for applying folders to cans. 10 While machines have previously been provided for this general purpose they have been difficult to operate because when a folder failed to feed, the feeding of folders was interrupted until attention was given to the machine and no folders 15 were applied to the cans passing through the machine during said interruption.

It is another object of my invention to provide a machine for applying folders to cans in which the feeding of folders will not be interrupted by the failure of a single folder to feed 20 and in which the normal feeding will be resumed as soon as the cause of said failure is corrected.

In the machines formerly provided for applying 25 folders to cans, a break in continuity of the stream of cans being fed through said machine resulted in the folder intended for that can being dropped into the machinery and damaged so as to be unfit for use.

It is yet another object of my invention to provide a machine for applying folders to cans which is adapted to receive and apply folders to an intermittent stream of cans without loss of said 30 folders.

The manner of accomplishing the foregoing 35 objects as well as further objects and advantages will be made manifest in the following description taken in connection with the accompanying drawings in which:

40 Fig. 1 is a fragmentary side elevational view of a preferred embodiment of my invention.

Fig. 2 is an enlarged side elevational view of the folder feeding and applying mechanism, there being portions of the folder applicator rotor 45 broken away to illustrate the means for utilizing suction in the operation of the applicator.

Fig. 3 is a plan view of the applicator rotor of the machine with the folder magazine removed and may be considered as a sectional view taken 50 on the line 3—3 of Fig. 2.

Fig. 4 is a vertical sectional view taken on the line 4—4 of Fig. 2 and illustrates the means for utilizing suction in the operation of the applicator rotor.

55 Referring specifically to the drawings, I shall

designate the folder applying machine illustrated therein by the reference numeral 10. This machine includes a frame 11 having a pair of channel beams 12 upon which rest a can track 13 having a chain groove 14 in which an endless 5 conveyor chain 15 of a conveyor 16 travels. The chain 15 is trained about sprockets 17, only one of which is shown, this sprocket being mounted on a shaft 18 by which the conveyor 16 is continuously driven. Certain links 19 of the chain 10 15, which links are uniformly spaced, have can pushers 20 provided thereon which extend upwardly when these links are disposed in the chain groove 14. Extending laterally from the track 13 are ears 22 upon which angle iron can guards 15 23 and 24 are adjustably secured by cap screws 25. Thus the guards 23 and 24 may be set closer together or farther apart to accommodate cans differing in diameter.

Provided on the can guide 24 is a vertical bearing 26, the purpose of which will be made clear hereinafter. This guide also has a relatively long narrow slot 27, explanation of which also will be deferred.

Rigidly mounted at their lower ends on the 25 frame 11 so as to extend vertically upward at the rear of the conveyor 16 is a pair of heavy screws 29. The screws 29 have nuts 30 which support an elevated frame 35 which can be raised or lowered by rotating the nuts 30. The elevated 30 frame 35 has bearings 36 and 37 in which shafts 38 and 39 are journalled. At the rear of the elevated frame 35, these shafts have sprockets 40 about which is trained an endless chain 41. Fixed 35 on the shaft 39 is a rubber gluing wheel 45 having four circumferentially spaced faces 46 which, as the shaft 39 rotates, are brought successively into tangential contact with a roller 47. This roller is mounted on the frame 35 on a horizontal axis parallel with the shaft 39 so as to extend 40 into a glue pot 48 also mounted on said frame.

Extending forwardly from the elevated frame 35 are magazine supporting arms 49 and 50 for a folder magazine 51. Mounted on an angle of approximately 45 degrees on the upper base of 45 the magazine supporting arm 50 is a magazine bottom plate 52 which has side arms 53 on which are adjustably mounted side guard rails 54 which are adapted to guide a supply of folders 55 when the latter is placed between the rails 54 so as to 50 rest on the bottom plate 52. Provided on the lower end of the bottom plate 52 is a brush 60 for preventing more than one folder being removed from the magazine at one time.

Secured to the supporting arm 49 by screws 61 55

is a spring magazine end plate 62 the lower end of which extends downwardly opposite the mouth of the magazine 51 and has a notch 63 provided therein. The supporting arm 49 has an adjustable stop screw 65 which extends upwardly through the support 51 and which determines the normal downward position of the end plate 62.

Fixed upon the supporting arm 49 as by cap 10 screws 70 is a bracket 71 having a vertical body 72. The body 72 has a notch 73 in the lower edge thereof and, forwardly from said notch, a bearing 74 in which is journaled a shaft 75 which is held in place by collars 76 and 77. Extending inwardly into the notch 73 past the collar 77 is a pin 78 formed eccentrically on the inner end of the shaft 75. This pin has a roller 79 rotatably mounted thereon. This roller is of such diameter as to rest constantly on the upper surface of the spring plate 62.

Fixed upon the outer end of the shaft 75 is an arm 85 having a blade 86. Secured to the upper face of the vertical body 72 is a bracket 87 on which is formed a vertical bearing 88. The bracket 87 is positioned in its relation to the body 72 so that the bearing 88 is in vertical alignment with the bearing 26 on the can guide 24.

Journaled in the bearings 26 and 88 is a vertical shaft 90 on which are fixed a can responsive arm 91 and an upper arm 92. The arm 91 is held inwardly by a spring 93 so that this arm extends through the slot 27 as shown in full lines in Fig. 3.

35 The outer end of the arm 92 is bent horizontally and has a notch 95 therein into which the blade 86 extends.

It is thus seen that the mechanism just described is actuated when the arm 91 shifts inwardly into its full line position as shown in Fig. 3 so as to rock the shaft 75 and lift the roller 79 thus releasing the pressure of the latter against the spring plate 62 and allowing this plate to spring upwardly into the position in which it is shown in Fig. 2. With this upward movement the spring plate 62 lifts the supply 55 of folders upwardly in the folder magazine with a result which will be made clear hereinafter.

Secured to the frame 35 is a stationary vacuum disc 98, having a central bore through which the shaft 38 extends. In its face 99 is a vacuum slot 100 having a restriction 101. Communicating with the upper, unrestricted portion of the slot is a pipe 102 which leads to a vacuum pump 53 (not shown). By reason of the restriction 101, the vacuum produced below the restriction is considerably less than it is above the restriction. Slightly beyond the lower end of slot 100 is a hole 105 extending through the vacuum disc to 60 provide an air vent the function of which is later described.

Fixed as by a pin 110 on the forward end of the shaft 38 is a folder applicator rotor or vacuum wheel 111 the face 111a of which is ground 65 to make a substantially air tight seal with the face 99 of the vacuum disc which is similarly ground.

The rotor 111 has a series of four bosses 112, outer cylindrical faces 113 of which are formed 70 concentric with the axis of the rotor 111. Formed in the face 113 of each boss 112 near the leading edge thereof is a suction mouth 114 which is connected to a duct 115 opening through the face 111a in alignment with the slot 100.

75 A suitable means is provided for rotating

shafts 38 and 39 which includes a sprocket 120 on the rear end of the shaft 38 and a chain 121. This chain is trained about this sprocket and about idler sprockets 122 and 123 to bring it into reverse engagement with a sprocket (not shown) on the rear end of shaft 28 so as to produce a timely rotation of the wheel 45 and rotor 111 relative to the travel of the conveyor 16.

Operation

10 Before beginning operations with the machine 10, the magazine 51 is furnished with a supply of folders 55 and the glue pot 48 is furnished with a supply of glue. The vacuum pump (not shown) which is connected to the pipe 102 is now actuated so as to draw a constant vacuum on the slot 100. The conveyor 16 is now set in motion and cans C are fed onto this conveyor so that insofar as possible there is a can propelled along in front of each of the pushers 20 20 when the latter are disposed over the can and track 13. As these cans proceed along the conveyor 16, the rotating wheel 45 brings the faces 46 thereof into contact with the periphery of the glue wheel 47 which applies glue to the faces 46. 25 In this manner glue is transferred to the top of each of the cans C as this can comes underneath the wheel 45.

30 As these cans progress, each one in turn comes in contact with the arm 91 so as to continually 30 maintain this positioned substantially as indicated by the dotted lines 130 in Fig. 3. The swinging outward of the arm 91 rocks the shaft 75 so as to shift the roller 79 and depress the spring plate 62, against which this bears, into the position in which the latter is shown in Fig. 1.

35 When the plate 62 is thus depressed the supply of folders 55 drop down in the magazine 51 until the lowermost folder is located in the path of the next advancing face 113 on the rotor 111. 40 With the rotation of the rotor that face 113 thus comes into face to face contact with the lowermost folder 55. The sucking of air inwardly through the suction mouth 114 in that face produces a semi-vacuum which takes hold of that folder and carries it with the rotor thereby removing it from the magazine. The rotation of the rotor being in timely relation with the conveyor 16, each boss as it swings downwardly extends right into the chine of a can as the latter 50 travels along the conveyor therebeneath. When a boss carries a folder as above described, the latter is pushed into the chine of the can against the spot of glue formerly applied by the glue wheel 45. Thus a folder is glued to the upper 55 end of each can passing along the conveyor 16.

60 As long as the machine 10 continues to be fed with an unbroken stream of cans C, and so long as an orderly supply of folders 55 is maintained in the magazine 51, the operation of the machine 65 goes on as above described. In the event of a break in the continuity of the stream of cans on the conveyor 16, by the omission of one or more cans from the stream, the arm 91 is not held out when the can spaces on the conveyor come along 65 which are vacant. The spring 93 thereupon shifts arm 91 inward, rotates shaft 90 which rocks shaft 75 to lift roller 79 and release spring plate 62. The latter now rises as shown in Fig. 2 thereby lifting the supply of folders 55 to where the 70 lowermost folder in the magazine lies beyond the reach of the advancing bosses 112. This prevents each boss, which is timed to have delivered a folder to a can in one of the vacant spaces on the conveyor, from taking a folder from the 75

magazine. Thus folders are not dropped into the machinery and wasted when breaks occur in the continuity of the stream of cans on the conveyor 16.

As soon as the next can comes along on the conveyor 16, however, it shifts the lever 91 outward again and depresses the spring magazine end plate 62 to lower the supply of folders into feeding position. The next advancing boss 112 accordingly picks up a folder from the bottom of the stack and applies it to the next can following the break. From here on the feeding of folders continues until one or more vacant spaces again occur in the stream of cans C whereupon the feeding of folders will be correspondingly interrupted but only to omit feeding folders to said vacant spaces.

The vacuum created in the upper unrestricted portion of the slot 100 exerts a strong suction in taking hold of a folder. As the rotor revolves, less vacuum is needed to retain the folder on the boss 112, and the vacuum transmitted through the duct 115 after it passes the restriction 101 is adequate. When the duct 115 passes the air vent 105 the vacuum is wholly destroyed at the suction mouth 114 at that particular position and the folder more readily deposited on the can.

As the slot 100 is long enough to communicate with two of the ducts 115 at one time, the absence of a folder from one of the mouths 114 would interfere with the vacuum and hinder its function, if no provision were made to maintain the vacuum notwithstanding. Under such a contingency the machine would have to be stopped, and the uncovered vacuum mouths be temporarily closed. My invention overcomes this difficulty by use of the restriction 101. The passage in this restriction is small enough so that even if the mouth of the duct 115 which is passing along the slot below the restriction is uncovered as by reason of the folder supply having been interrupted due to the absence of a can, or for other failure, the vacuum in the upper portion of the slot is not materially impaired and will continue to function.

This latter feature is of advantage not only in resuming the feeding of folders after a break in the stream of cans on the conveyor 16, but in a resumption of the folder feeding no matter what the cause had been for its interruption. Sometimes, for instance, the folders might be stuck together and thus the bottom folder would not feed out when engaged by the rotor. Where any such thing occurs in my invention, the supply of folders merely needs to be straightened out in the magazine and the feeding will automatically be resumed without any halt in the operation being necessary. If any cans should go through without getting folders during such an interruption in the feeding of folders, these cans can readily be supplied with folders by hand, as the top surface of each can has already been spotted with glue.

What I claim is:

1. In a machine for applying folders to cans, the combination of: conveyor means for conveying a series of cans along a given path; magazine means for containing a multiplicity of folders; rotary suction means for removing folders one by one from said magazine and applying said folders to said cans, said rotary means having a plurality of circumferentially spaced suction mouths each of which is adapted to remove a folder from said magazine when it is disposed adjacent thereto and apply said folder to one of said cans; means

for sucking air inwardly through each of said suction mouths as the latter comes opposite said magazine and maintaining said suction until the folder removed by said last mentioned mouth from said magazine has been applied to a can; and means for restricting communication between said suction means and each of said suction mouths when the latter is between folder receiving and folder applying positions and as the next following suction mouth approaches folder receiving position.

2. In a machine for applying folders to cans, the combination of: a conveyor for feeding a series of cans along a given path; a magazine for holding a multiplicity of folders; a rotor having a plurality of circumferentially spaced suction mouths thereon, each of said mouths being adapted to receive a folder from said magazine and apply it to a can; suction means including a slot, there being ducts in said rotor connecting each of said mouths with said slot when said mouth is brought into operative relation with said magazine, said slot providing a substantially restricted communication between said suction means and each of said ducts when the mouth served by said duct is moving between folder receiving and folder applying positions; and means for coordinately rotating said rotor and operating said conveyor.

3. In a machine for applying folders to cans comprising can conveying means and a magazine for retaining folders in position to be fed, a vacuum wheel having circumferentially spaced suction mouths rotatably passing in proximity to the folder magazine and adapted to successively withdraw folders therefrom and deliver same to a position for application to cans, a continuous suction means having an arcuate passage with an intermediate restriction therein, and ducts in the vacuum wheel communicating with the suction mouths and with the arcuate passage by which a strong suction and subsequently a weaker suction is created at the suction mouths during rotation of the wheel.

4. In a machine for applying folders to cans comprising can conveying means and a magazine for retaining folders in position to be fed, a vacuum wheel having circumferentially spaced suction mouths rotatably passing in proximity to the folder magazine and adapted to successively withdraw folders therefrom and deliver same to a position for application to cans, a vacuum and control means cooperating with the suction wheel to create a strong suction at the vacuum mouth in proximity to the folders, a weaker suction beginning at a point of rotation intermediate between folder receiving and folder applying positions, an air exhaust at folder applying position, and no suction between the latter position and the point of starting.

5. In a machine for applying folders to cans comprising can conveying means, a magazine for retaining folders in position to be fed, and means shifting the folders out of such position in the event a can is not present to receive the folder, a vacuum wheel having circumferentially spaced suction mouths rotatably passing in proximity to the folder magazine and adapted to successively withdraw folders therefrom and deliver same to a position for application to cans, the vacuum being partially maintained by the folders covering the suction mouths, and means for partially sustaining the vacuum sufficiently for succeeding operative purposes in the event no folder is fed to a suction mouth.

6. In a machine for applying folders to cans comprising can conveying means, a magazine for retaining folders in position to be fed, and means shifting the folders out of such position in the event a can is not present to receive the folder, a vacuum wheel having circumferentially spaced suction mouths rotatably passing in proximity to the folder magazine and adapted to successively withdraw folders therefrom and deliver same to a position for application to cans, the vacuum being partially maintained by the folders covering the suction mouths, and being temporarily impaired if no folder is fed to a suction mouth, means partially restoring the vacuum in such latter event prior to the next succeeding vacuum mouth reaching the folder receiving position.
7. In a machine for applying folders to cans comprising can conveying means, a magazine for retaining folders in position to be fed, and means shifting the folders out of such position in the event a can is not present to receive the folder, a vacuum wheel having circumferentially spaced suction mouths rotatably passing in proximity to the folder magazine and adapted to successively withdraw folders therefrom and deliver same to a position for application to cans, the vacuum wheel having a flat face and ducts leading from the suction mouths and opening into the said face, a vacuum disc having a surface hermetically engaging the said wheel face and provided with an arcuate slot located in the path of said openings, a continuous suction means withdrawing air from one end of said slot, and a restriction in the slot between the ends thereof reducing the communication of suction from one side of the restriction to the other.
8. In a machine for applying folders to cans comprising can conveying means, and a magazine for retaining folders in position to be fed, a vacuum wheel having circumferentially spaced suction mouths rotatably passing in proximity to the folder magazine and adapted to successively withdraw folders therefrom and deliver same to a position for application to cans, the vacuum

wheel having a flat end face and ducts leading from the suction mouths and opening into the said face, a stationary vacuum disc having a surface hermetically engaging the said wheel face and provided with an arcuate slot located in the path of said openings, a continuous suction means withdrawing air from one end of said slot, and a restriction in the slot between the ends thereof reducing the communication of suction from one side of the restriction to the other.

9. In a machine for applying folders to cans comprising a can conveyor, a folder magazine having a bifurcated end plate supporting the lowermost of a stack of folders, a vacuum wheel with circumferentially spaced suction mouths rotatably passing in proximity to the lowermost folder between the bifurcations of said end plate to withdraw the said folder from the magazine, spring means tending to urge the magazine end plate away from the suction mouths to render them inoperative to withdraw folders, and a mechanism actuated by the presence of a can in position to receive a folder opposing the spring means to render same ineffective.

10. In a machine for applying folders to cans comprising a can conveyor, a folder magazine having a bifurcated end plate supporting the lowermost of a stack of folders, a vacuum wheel with circumferentially spaced suction mouths rotatably passing in proximity to the lowermost folder between the bifurcations of said end plate to withdraw the said folder from the magazine, spring means tending to urge the magazine end plate away from the suction mouths to render them inoperative to withdraw folders, and a mechanism actuated by the presence of a can in position to receive a folder opposing the spring means to render same ineffective, the control comprising a cam engaging the spring, and can engaging means operating the cam.

HERBERT W. KAGLEY.
